CLAIM

The ornamental design for a sconce, as shown and described.

DESCRIPTION

FIG. 1 is a perspective view of the new design for a sconce;

FIG. 2 is a front elevational view thereof;

FIG. 3 is a top plan view thereof;

FIG. 4 is a bottom plan view thereof;

FIG. 5 is a right side view thereof, the left side view being rotationally symmetric; and,

FIG. 6 is a rear view thereof.

The broken line disclosure is for environmental purposes only and does not form a part of the claimed design.

1 Claim, 6 Drawing Sheets
